UNITED STATES PATENT OFFICE.

EDWARD P. DAY, OF NEW YORK, N. Y.

MACHINE TO PRINT SUBSCRIBERS' NAMES, &c., ON NEWSPAPERS.

Specification of Letters Patent No. 11,022, dated June 6, 1854.

To all whom it may concern:

Be it known that I, EDWARD PARSONS DAY, of the city, county, and State of New York, have invented a new and useful Improvement on Henry Moeser's Machine for Printing Names of Subscribers on Newspapers, &c., patented June 24, 1851, and assigned to me November 23, 1853; and I do hereby declare the following to be a full description of 10 the same.

Mr. Moeser's arrangement is a long composing trough, having one name only in a row, and therefore requiring twenty operations to print twenty names for one post office. To obviate this difficulty by increasing the width of the composing trough would make the machine too heavy to operate, as the weight of the trough would be increased so much, that it would be too heavy for one 15 man to labor at, if the size of the composing trough were made equal to the setting up of 5,000 names, (the capacity of my machine) as the weight of the trough has to be moved horizontally and with rapidity, at 20 the same time the impression of the type is taken. My invention is to overcome this objection, and to do so I make a composing cylinder of suitable diameter and length to admit of setting up 5,000 names. In the 25 face of the cylinder I cut grooves into which the type are set, and by means of a binding screw to each row of type I hold them firmly in the groove. This cylinder is arranged on an axis and supported in boxes 30 in the end parts of the machine. To rotate the cylinder I use a ratchet wheel on the end of the axes of the cylinder, and by means of a pawl attached to a lever for operating the platen, or acting independent of the 35 platen, I move the cylinder forward one row of type at each impression. By this improvement I save great space in shop room as the type cylinder to contain 5,000 names will only be three feet in diameter by four 40 feet long, while a composing trough to contain the same number of names would have to be nine feet long by four feet wide. Second, I save great labor as my composing cylinder, being nicely balanced on its axis, 45 would rotate with but a few pounds of power expended, while the composing trough of iron nine feet long, by four feet wide would make a weight of several hundred pounds to be moved in a horizontal position, 50

which of course shows the utter want of 55 practicability of the machine to print the subscription lists of such papers as the *N. Y. Herald, Tribune*, etc., having from 20,000 to 100,000 papers to mail every week and usually allowing but two to three days in 60 the offices now to do it by writing them. But to describe my invention more particularly I will refer to the accompanying drawings forming a part of this schedule the same letters of reference wherever they occur referring to the same parts. 65

Figure 1, is a front elevation of the machine. Fig. 2, is an end elevation of the machine. Fig. 3 is a plan elevation of the machine. Fig. 4, is a cut section of the machine through the line *x, x*, Fig. 3. 70

Letter A, is the frame of the machine.

B, is the type cylinder, and C, is the axis of the cylinder, secured in boxes, in the end posts of the frame. This cylinder is made 75 of metal, and when large is formed of segment plates, bolted to arms extending from the axis. In the face of the cylinder is cut a series of grooves D, D &c. of suitable size and depth to admit the type being set in 80 them. These type are held in their places by binding screws E, E &c. passing through the end of the cylinder, and against the side of the type. 85

Letter F, is a ratchet wheel secured on the 85 end of the cylinder axis, and G, is a lever, working loosely on the cylinder axis and having a pawl H, attached to it for working the ratchet wheel, for the purpose of rotating the type cylinder. 90

Letters I, I, are two stops arranged in arms J, J, projecting from the frame of the machine, for the purpose of regulating the distance through which the face of the type wheel moves at each impression. This arrangement of moving the type wheel may be dispensed with, and by a lever and pawl arrangement, worked by the lever K, at the same time it works the platen L, the type cylinder can be moved forward the required 95 distance, while the platen is being drawn back after taking the impression. 100

Letters M, M, are guideways in which the platen works.

Letter N, is the fulcrum to which the lever 105 K, is attached.

P, is a brace across the head of the machine through which is a stud R, attached

to the platen—on the head of this stud is a spiral spring S, the object of which is to react the platen after the impression has been taken. Letter T, is a table, on which 5 the papers are arranged for printing.

The operation of the machine is first, all the names for one post office are set up in one groove, and the name of the post office. The papers are then folded of proper size 10 exposing a part of the heading margin, and placed on the table, so that the margin laps over the face of the type in the cylinder. A wrapper is then folded, so as to have the back printed, when placed in the machine, 15 and is also placed on the table and laps over the type. The platen is now forced down by the operator, and as the type have been previously inked, the names of the subscribers and post office where intended to be 20 sent at all printed. When the impression has been taken the papers are rolled up in

the wrapper and pasted ready for the post office.

Having now described my invention I will state what I claim and desire to secure by 25 Letters Patent is—

The type cylinder having a series of type grooves cut in its periphery and parallel to its axis, and binding screws in the cap or end plate of the cylinder for adjusting the 30 type in the cylinder grooves in combination with the table, platen and ratchet wheel for holding the paper, and printing and rotating the cylinders as an improvement on Henry Moeser's invention for like purposes, and 35 whereby all the names of a subscription list for one post office, and the address of the post office, may be printed at one operation.

EDWARD PARSONS DAY.
